UNITED STATES PATENT OFFICE

SIDNEY ROSENTHAL, OF CEDARHURST, NEW YORK

DESIGN FOR A BUTTON

Application filed June 6, 1932. Serial No. 43,999. Term of patent 3½ years.

To all whom it may concern:

Be it known that I, SIDNEY ROSENTHAL, a citizen of the United States, residing at Cedarhurst, L. I., in the county of Nassau and State of New York, have invented a new, original and ornamental Design for a Button of which the following is a specification; reference being had to the accompanying drawing, forming part thereof.

Fig. 1, is a plan view of a button, showing my new design.

Fig. 2, is a side view thereof.

I claim:

The ornamental design for a button, as shown.

SIDNEY ROSENTHAL.
